UNITED STATES PATENT OFFICE.

AUGUST BRÜGGEDEANN, OF BRESLAU, GERMANY, ASSIGNOR TO THE DEUTSCHE WAFFEN-UND MUNITIONSFABRIKEN, OF CARLSRUHE IN BADEN, GERMANY.

ELECTRIC RELEASING APPARATUS FOR PNEUMATIC-PRESSURE BRAKES.

SPECIFICATION forming part of Letters Patent No. 687,297, dated November 26, 1901.

Application filed August 2, 1900. Serial No. 25,870. (No model.)

To all whom it may concern:

Be it known that I, AUGUST BRÜGGEDEANN, a subject of the King of Prussia, German Emperor, and a resident of Breslau, Germany, have invented certain new and useful Improvements in Electric Releasing Apparatus for Pneumatic - Pressure Brakes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Pneumatic-pressure brake apparatuses as hitherto used have the disadvantage that the brakes fail to work wholly or in part should the air-pressure in the train-pipe not be duly maintained or should the air-pipe of a part of the train be shut off from that of the engine by the stop-cocks being partly or entirely closed maliciously or accidentally. The store of braking power of the part of the train-pipe thus separated then gradually decreases without causing the brakes to work, nor can the engine-driver work the brakes by making use of the driver's valve.

This invention relates to an electric means of causing pneumatic brakes to be applied, and has for its object to automatically cause the train to stop should the train-pipe be interrupted, as above mentioned. The apparatus, which is placed at the rear part of the train, is such that when the air-pressure in the train-pipe decreases to a certain degree a manometer closes the circuit of a battery and causes the armature of an electromagnet to open an air-releasing valve. In the example illustrated a valve on the "Chapsal" system, United States Patent No. 555,075, dated February 25, 1896, has been chosen, (*Revue Industrielle*, 1896, page 64; *Organ für die Fortschritte des Eisenbahnwesens*, 1896, page 148;) but it is to be understood that any other well-known construction of valves may be employed.

In the accompanying drawings, forming part of this specification, Figure 1 is a vertical section through the apparatus. Fig. 2 shows the

contacts at the bottom part of the same. Fig. 3 shows the apparatus attached to the last carriage of the train. Figs. 4 and 5 are sections illustrating the action. Fig. 6 shows a diagram of the electric circuit.

The apparatus comprises a battery *a* or other source of electricity, an electromagnet *b*, with an armature *d*, acted on by a spring *c*, pin-valves *e* and *f*, carried by the armature, and a chamber *g*, with valve-operating diaphragm *h*, (or it may be a piston,) and the air-releasing valve *i* operated thereby. To this is added in the present apparatus a manometer *k* or a similar device arranged, together with the contact devices *p* *r* *q*, inside the battery-casing. The improved apparatus, which is suspended, say, from the buffer-rod of the last carriage of the train, is coupled with the train-pipe of the last carriage by a coupling-pipe *l*, (see Fig. 3,) which is connected with the short pipe leading to the chamber below the air-releasing valve *i*. When the brake-reservoirs are charged, the compressed air from the train-pipe passes through passage *m* and presses on the piston *n* of the manometer *k*, forcing the piston-rod outward against the pressure of spring *o*. Other forms of manometer may be used in connection with passage *m*.

In the arrangement shown in Fig. 1 an inclined cam *q*, of insulating material, attached to the rod of piston *n*, pushes aside the spring-terminal *r* when it moves in the direction of the arrow. This terminal is carried by a spring *s*, attached to an arm *t*.

p is a stationary terminal let into the heel end of the insulating-cam *q*, so that when the piston moves quickly to the position shown in Fig. 4 the terminal *r* springs back clear of the terminal *p* without touching it, thus leaving the electric circuit still broken. As long as normal air-pressure is maintained in the train-pipe the piston *n* remains in the position shown in Fig. 4, the terminals *p* and *r* remaining still out of contact. As soon as the air-pressure in the train-pipe begins to diminish the piston *n* is forced inward by spring *o* and the terminal *p* approaches *r*. When terminal *p* encounters terminal *r*, as in Fig. 5, the circuit of battery *a* is com-

pleted through the wires u and v and the electro-magnet b , which attracts the armature d , whereupon the pin-valve e is raised from its seat and admits compressed air from the 5 train-pipe through passage x into the space z and thence into the diaphragm-chamber g . The diaphragm h is thus caused to open the air-releasing valve i and allowing the air to escape from the train-pipe through the aper-tures w , the sudden decrease of pressure in 10 the train-pipe effecting a rapid braking of the train. When by the further movement of the piston n , consequent on the fall of pressure in the train-pipe, the terminal r is 15 pressed by the insulator q against a pair of stationary inclined cams y , it is forced or squeezed outward, so as to allow the heel end of q to pass to the position shown in Fig. 1. The position of terminal p is such that the 20 engine-driver may decrease the air-pressure in the train-pipe as required during ordinary working without causing the terminals p and r to make contact, which is only effected automatically and when the air-pressure in the 25 train-pipe falls below that required for ordinary braking purposes. If it is desired that the train-conductor or a traveler should be enabled to open the discharge-valve i in case of emergency, it is only necessary to provide 30 means of completing the electric circuit through the wires u and v , as shown in the diagram, Fig. 6, by means of switch r^2 and contact p^2 .

Having now particularly described my in- 35 vention, what I claim, and desire to secure by Letters Patent, is—

1. In an air-brake system, the combination with the train-pipe, of a manometer and an electrically-operated outlet-valve connected 40 therewith, and means connected to said manometer to close circuit through said valve to decrease pressure in the train-pipe when said pressure falls below working pressure, thereby operating the brakes, substantially 45 as described.

2. In an air-brake system, the combination with the train-pipe, of a manometer and an electrically-operated valve connected therewith, a suitably-arranged fixed contact and 50 a movable contact operated by said manometer and organized to operate said valve when the circuit is closed through the contacts, thereby venting the train-pipe and causing the brakes to be applied, substan-tially as described.

3. In an air-brake system, the combination with the train-pipe, of a manometer and electrically-operated valve connected therewith, a suitable fixed contact and a movable contact on the manometer organized to close circuit through said valve when the contacts touch, and one or more parallel circuits, each arranged to close circuit through said valve independently, thereby venting the train-pipe and applying the brakes, substantially 65 as described.

4. In an air-brake system, the combination with the train-pipe, of an electrically-operated valve and a spring-controlled manometer connected therewith, a suitably-arranged 70 electrical terminal, and a movable electrical terminal held out of contact with the former by air-pressure and organized to close circuit through said valve by a predetermined de-crease of pressure in the train-pipe, thereby 75 venting said train-pipe and applying the brakes, substantially as described.

5. In an air-brake system, the combination with the train-pipe, and an electrically-operated valve connected therewith, of a spring-actuated piston and rod normally held by working air-pressure from the train-pipe, a 80 spring-contact and a contact carried by said piston-rod and organized to close circuit through said valve to vent the train-pipe and 85 apply the brakes, substantially as described.

6. In an air-brake system, the combination with the train-pipe and an electrically-operated valve, of a spring-controlled manometer, comprising piston and rod normally held 90 by air-pressure, an electrical contact secured to a wedge-shaped insulating nosepiece on the piston-rod, a pair of guides provided with inclined faces between which said insulated piece is arranged to move, a spring-held 95 roller contact held against the inclined faces of said guide, said nosepiece arranged to ride under the roller when moved in one di-rection and in the other to contact therewith and cause said roller to ride upon the inclined 100 surfaces of the guides past the contact there-on, to close circuit through the valve, sub-stantially as described.

In testimony that I claim the foregoing as my invention I have signed my name in pres- 105 ence of two subscribing witnesses.

AUGUST BRÜGEMANN.
